APPARATUS FOR MAKING SOAP CAKES
HAVING DESIRED INSIGNIALeslie A. Block, Rochester, N. Y.; Wilton A. Block,
administrator of said Leslie A. Block, deceasedOriginal application September 25, 1943, Serial
No. 503,792. Divided and this application Feb-
ruary 26, 1945, Serial No. 579,706

10 Claims. (Cl. 25-7)

1

The present invention relates particularly to an apparatus for making soap cakes having a desired insignia and the present application is a division of my co-pending application Serial No. 503,792 filed September 25, 1943.

While it is well-known that soap cakes having a desired insignia may be made by providing an aperture or recess in a soap cake and introducing a distinctively colored insert thereinto, such known methods and apparatus are not satisfactory because exact and precise registry is not obtained between the insert and the soap cake.

The primary object of the present invention is the provision of an apparatus for making a soap cake having a desired insignia which is precisely complementary to said soap cake.

Another object of the invention is the provision of an apparatus for introducing a distinctive insert into a soap cake and simultaneously forming and/or reforming the aperture or recess in the soap cake by means of the distinctive insert itself.

A further object of the invention is an apparatus for providing a distinctive soap material with the grain therein in a predetermined plane and forming from such distinctive soap material an insert which is introduced into the soap cake with the grain of said insert substantially parallel to the display surface of said soap cake.

A still further object is an apparatus comprising a mold with a cavity for a soap cake and having a wall provided with an aperture having the contour of a desired insignia and a plunger for moving a distinctive insert through said aperture and into said soap cake.

Other and further objects of the invention will be apparent or suggested to those skilled in the art by the description which follows:

The aforementioned and other objects of the invention are accomplished by an apparatus for introducing a distinctive insert into a soap cake and simultaneously forming or reshaping an aperture in the soap cake by insertion of said distinctive insert so that the contour of the aperture and insert correspond precisely throughout. The technique of the invention is further enhanced by forming the distinctive insert of a soap material which is harder and drier than the soap cake, by previously providing an aperture in the soap cake which aperture is more or less reshaped by the insert itself, by forming the insert in a die molded around the core for making said aperture, by arranging the grain of the soap material for the distinctive insert in a predetermined plane, either by pre-arrangement or by

2

compression, and forming therefrom an insert which is introduced into the soap cake with its grain parallel to a display surface of the soap cake, and/or by introducing the freshly formed insert immediately into the soap cake to shape the aperture therein whereby the adjacent surfaces of the insert and aperture contact throughout and tightly adhere to each other.

The insertion and cementation of the distinctive inserts may be facilitated or improved by lubricating or wetting the walls of the aperture in the soap cake prior to or during the introduction of the distinctively colored insert into said soap cake. Also the fixation of the distinctively colored insert and the appearance of the composite soap cake may be further improved by subjecting said composite cake to a compressing and finishing operative in a cake finishing press of known design.

As used herein the term "insignia" shall mean and include one or more symbols, monograms, figures, letters, characters, trade-marks, designs, or the like; the term "distinctive" as used to describe the insert shall mean and refer to a different color or different shade of the same color for the insignia with respect to the color of the soap cake; and the words "aperture," "recess," "hole," etc. are applied interchangeably to the openings in the soap cake. The features of the invention are equally advantageous whether, as shown, the distinctive inserts extend partially or entirely through the soap cake.

Since the present invention is primarily directed to formation of a soap cake having a desired insignia, it is not necessary to describe the preparation and manufacture of the soap material itself. The only requirement is that the soap material shall be in a state ready and suitable for molding and may be in pulverized or powdered form. For instance, soap material as it comes from the plodder may be used as a starting material especially for the cake body while the soap material for forming the insignia may be dyed to a color and/or shade different from the soap cake by the addition or admixture of suitable dyes or pigments and is preferably dried or dehydrated in a known manner to be drier and harder than the soap material of the cake body.

Reference is hereby made to the accompanying drawings wherein similar reference characters designate similar elements and wherein:

Fig. 15 is a side elevation of the automatic machine for practising my invention showing the actuating mechanism for the cake perforating and insert injecting stations thereof.

Fig. 16 is an inverted perspective view of the cutting and plunger members of the insert cutting and injecting station.

Although provision of recesses or apertures in the soap cake prior to the insertion of the distinctive inserts is shown herein and is preferred, it must be understood that the invention in its broadest aspects contemplates displacement of the soap material of the soap cake to receive the distinctive inserts solely by the action of the inserts themselves. However, the soap cakes may be provided with apertures extending completely through the cake or may be provided with recesses extending only part way through the soap cake. Such apertures or recesses may also be provided either when the soap cake is formed or may be provided by a punching operation later to be described.

The automatic machine for performing the method of the invention comprises a frame including side walls 73, see Fig. 15, and a carrier for a plurality of mold members which are moved to various stations such as a loading station, a cake perforating station, and an insert forming or cutting and injecting station. Such a carrier may comprise a pair of disks 45, see Figs. 1 and 15, mounted in spaced relation on and for rotation about a fixed shaft 46 which is mounted between the side walls 73 of the frame of the machine. A cam member 47 is fixedly mounted between said disks 45, includes a collar 48 attached to said

fixed shaft 46, and includes a rise 49 for a purpose to be mentioned later.

Each of the mold members is mounted between said disks 45 and each mold member comprises 5 a hollow frame 50 and a bottom member 51. Said hollow frame 50 provides a mold cavity 52, has end walls 53 which are fastened to said disks 45 and has side walls 54. The bottom member 51 fits into said frame 50 to close one side of said mold cavity 52 and has a stem 55 movable within a block member 56 mounted between said disks 45. Said bottom members 51 are normally held in any suitable manner with the ends of stems 55 bearing against the periphery of cam member 47. An indexing mechanism for the carrier may comprise a Geneva gear 74 mounted on one of said disks 45 and a driving member including a disk 75 carrying a pin 76 for engaging the radial slots of said Geneva gear 74 to move the same intermittently and a sector 77 on disk 75 engages the periphery of gear 74 to hold the same stationary between rotations thereof.

The loading station may comprise a conveyor 57 which brings the soap cakes 29 into position 25 opposite the cavity 52 in the mold member at the loading station and a loading plunger 58 is reciprocated within a support 59 to push the successive soap cakes 29 into said cavity 52 of the mold member. Whereupon the disks 45 are rotated to 30 bring the mold member and soap cake therein to a perforating station.

The provision of a perforating step or station for the soap cake 29 is optional because the apertures or recesses 65 may be provided in said soap 35 cake 29 prior to its being placed on the conveyor 57 of the loading station or because such apertures or recesses are not necessary when the distinctive inserts themselves perforate the soap cake at the insert forming or cutting and injecting station in the manner suggested herein.

Such a perforating station, if provided, may comprise a cover member 60 and a perforating member. Said cover member 60 has a cake contacting portion 62 and a pair of dowels 63. The perforating member includes a plunger 64 having the contour of the desired insignia and mounted upon a plate 64.

The actuating means for said cover and perforating members includes a frame head 78, a 50 pair of actuating rods 79 extending through said head 78 and attached to the cover member 60, and an actuating rod 80 also extending through head 78 but attached to the plunger plate 64. Coil springs 81 encircle rods 79 and a coil spring 82 55 encircles rod 80, and the tension in said springs 81 and 82 may be adjusted respectively by nut members 81' and 82' to cause the sequence of movements about to be described. Cheek plates 118, see Fig. 15 are attached to each side of the 60 frame head 78 by bolts 119 and slidably engage the sides of openings 120 in the side walls 73. A connecting rod 121 is pivotally connected at one end to a cheek plate 118 and at its other end to a bell crank 122 which is pivoted upon side wall 73 65 and which is oscillated by a second connecting rod 123 also connected to bell crank 122 and eccentrically pivoted to a driving disk 124.

During each cycle of the machine said actuating means moves the head 78 toward and away 70 from the carrier for the mold members. Movement of the head 78 toward a mold member moves the actuating rods 79 through compression of springs 81 to project the cake contacting portion 62 and dowels 63 of the cover member 60 75 into the mold cavity 52 and recesses 63' respec-

tively. At the same time, the plunger 61 is moved toward the soap cake 29 and continued movement of head 72 through spring 82 and actuating rod 80 moves plate 64 to project perforating plunger 61 into the soap cake 29. Plunger 61 is moved into the soap cake 29 to any desired depth, preferably that indicated by the dotted lines in Fig. 2, or somewhat more than half way through the soap cake 29. Such depth of penetration of plunger 61 being determined by the eccentricity of the connection of rod 123 to disk 124 and/or by the radii of the arms of the bell crank 122.

Return of the frame head 72 to the position shown in Figs. 1 and 15 retracts said plunger 61 and cover member 60 from the mold member and the soap cake therein is provided with one or more apertures 65 in the shape of the desired insignia.

The insert forming and injecting station is also slidably mounted within openings 128 in the side walls 73 of the machine frame. Cheek blocks 125 are fastened to opposite sides of a frame head 72 by means of bolts 126 and dowel pins 127, see Fig. 10. A support member 67 is fastened at opposite ends to side walls 73 by bolts 68. Said insert forming and injecting station comprises a cover member 69, a plunger member 70, a piston member 71, and an actuating means for operating said members in a cycle composed of five steps. Said actuating means includes a frame head 72 which is reciprocated radially of the mold member carrying the soap cake 29 and a plurality of rods extend through said frame head 72 and beyond the support member 67.

The cover member 69 comprises a block 83 having a projection 84 adapted to fit into the hollow frame 50 and having a concave soap cake engaging surface 85. Said block 83 is provided with an insert soap cavity 86 and with a guideway 87 for conducting a strip 88 of a distinctively colored soap over said cavity 86. One or more apertures 89 having the shape or contour of the insignia to be embedded in the soap cake, are provided in said projection 84 and extend from the bottom of cavity 86 to the soap engaging surface 85 of the cover member 69. A slideway 90 is provided in the bottom of block 83 for a slide 91 which extends beyond one end of said block 83 and which is there provided with a pair of slots 92. The other end of slide 91 carries a pair of pins 93 which extend into recesses 94 in block 83. Springs 95 in said recesses 94 have one end connected to said pins 93 and the other ends connected to a pair of pins 96 within recesses 94 to hold the slide 91 normally in position against one of dowels 83' and with an opening 97 in said slide 91 opposite the apertures 89 in said projection 84. Slide 91 is also provided with an elongated slot 91' for permitting movement of slide 91 with respect to the other dowel 83'.

A pair of actuating rods 98 are attached to diagonally opposite corners of the block 83 of the cover member 69 and each extends upwardly through the frame head 72 and through and beyond the support member 67. A pair of coil springs 99 encircle said actuating rods 98 above said support member 67 and a pair of nuts 100 are threaded onto the upper ends of said rods 98. Another pair of nut members 98' are threaded onto rods 98 to limit the upward movement thereof under the action of springs 99. A second pair of coil springs 101 encircle rods 98 between the ends of the frame head 72 and a nut 102 is threaded on each rod 98 for adjusting the ten-

sion in said springs 101 between the bottom of frame head 72 and said nuts 102.

The piston member 71 comprises a plate 103 and a piston 104 adapted to fit into the cavity 86 in said block 83. Said piston 104 is attached to or is integral with plate 103 and extends downwardly therefrom. Also the piston 104 is provided with one or more apertures having the shape and contour of the desired insignia. The plate 103 is provided at one pair of diagonally opposite corners with openings through which the actuating rods 98 slidably extend and a second pair of actuating rods 105 are attached to the other pair of diagonally opposite corners of plate 103 and such rods 105 extend upwardly through the frame head 72. A coil spring 106 encircles each of said rods 105 between the top of said frame head 72 and a nut 107 is threaded onto each of rods 105. A nut member 108 is also threaded onto each of rods 105 between the ends of frame head 72 and each is adapted to abut the bottom end thereof.

The plunger member 70 comprises a plate 109 and one or more plungers 110 which have the same shape and contour as the desired insignia and which fit into the apertures in piston 104 and are adapted to fit into the apertures 89 in the projection 84 of the cover member 69. Said plungers 110 are attached to or are integral with plate 109 and extend downwardly therefrom. Said plate 109 is provided near its corners with holes through which extend the actuating rods 98 and 105 of the cover member 69 and of the piston member 71, respectively. An actuating rod 111 is attached at its lower end to the center of plate 109 and extends upwardly through the frame head 72. A coil spring 112 encircles said rod 111 between a nut 113 threaded thereon and the upper portion of frame head 72. An adjusting nut 114 is also threaded onto rod 111 and is adapted to abut against the lower portion of frame head 72. A pair of abutments 109' are adjustably attached or threaded into plate 109 and extend downwardly therefrom for a purpose to be described.

The slide 91 may be automatically operated in any suitable manner as by a pair of cam members 115 mounted upon the plate 109, extending downwardly through the slots 92 in slide 91, and each having a rise 116 at the lower end thereof.

The frame head 72 of the insert forming and injecting station is slidably mounted in the frame of the machine and is reciprocated in timed relation to the indexing means for the mold carrier. A pair of flanged cheek blocks 125 are fastened to opposite sides of head 72 by means of bolts 126 and dowel pins 127, see Fig. 10. Said blocks 125 engage and slide within rectangular openings 128 which are provided in side walls 73 of the machine frame. Pins 129 extend laterally from each block 125 and are each journaled in one end of a connecting rod 130 having its other end pivotally connected to a bell crank 131 which is rotatably mounted in common with bell crank 122 on a shaft 132 extending between the side walls 73, see Fig. 15. A second connecting rod 133 has one end connected to bell crank 131 and has its other end eccentrically pivoted to the driving disk 124. Said driving disk 124 is mounted upon a shaft 134 journaled in side walls 73 and driven in any suitable manner by a prime mover or motor, not shown.

Rotation of shaft 134 and driving disk 124 reciprocates connecting rods 133 and 130 and bell cranks 122 and 131 whereby cheek blocks 125 and

frame head 72 are reciprocated through a stroke determined by the eccentricity of the connection of connecting rod 133 to disk 124, and/or by the radii of the arms of bell crank 131 to which the connecting rods 120 and 133 are connected.

The actuating means for the insert forming and injecting station and/or for the cake perforating station are operated in timed relation to the indexing means for the mold carrier. For this purpose a sprocket 135 on shaft 134 is encircled by a chain 136 which also encircles a sprocket 137 attached to the driving disk 75 for the Geneva gear 74. As a result, the driving pin 76 moves said Geneva gear 74 when the cheek plates 118 and cheek blocks 125 and the associated frame heads 78 and 72 are at the uppermost ends of openings 129 and 128 and when the mold and/or soap cake engaging members of said stations are retracted and spaced from the mold members of the intermittently rotated carrier.

The operation of the insert forming and injecting station shown in Figs. 1 and 5-10 will now be described.

At the beginning of the cycle, the actuating means for and members of the insert forming and injecting station are in the positions shown in Fig. 1, the frame head 72 of said actuating means is in its uppermost position, the cover member 69 is spaced from the mold frame 50, piston member 71 is spaced from the bottom of guideway 87 sufficiently for introduction of the strip 88 of insert soap therebetween, plunger member 70 has the lower face or faces of the plunger 110 approximately flush with the bottom of piston 104, and the rises 116 on cam members 115 are in engagement with the outer ends of slots 92 to hold slide 91 outwardly against the action of spring 95 so that said slide 91 covers the apertures 89 in projection 84 of the cover member 69. At this time the coil springs 99 and 101 are under tension and hold the cover member 69 away from the mold member and nut members 98 abut against support member 67.

The first step of the insert forming cycle of the machine is illustrated in Fig. 5 and takes place during the first part of the downward movement of frame head 72 of the actuating means. During such movement of frame head 72 the compression on springs 106 and 112 is increased to exert a thrust on actuating rods 105 and 111, to move plates 103 and 109 toward the block 83, and to move piston 104 and plunger or plungers 110 through the strip 88 of insert soap into the cavity 86 in block 83. The volume in the strip 88 sheared off and pressed into cavity 86 is approximately equal to the volume of the insignia and the thickness of strip 88 and/or the amount of the strip 88 fed into said cavity 86 may be varied to maintain the relationship for insignia of different volume. The compression of the insert soap within the cavity 86 also arranges or orients the grain of the soap for the inserts so that such grain will be perpendicular to the pressure exerted by the piston and plunger members. When starting up the machine, it will obviously be necessary to fill cavity 86 with insert soap or several sections of strip 88 of insert soap.

In accordance with one form of the invention the insert soap may be of a harder and/or drier soap material than that constituting the base cake. Also the grain in the insert strip 88 is preferably in a plane perpendicular to the path of movement of the plunger member 70 and the piston member 71. In addition the springs 106 and 112 are so selected and arranged that the

approximately flush relationship is maintained between the bottom faces of piston 104 and plungers 110 during this first step so that there will be no disturbance of the grain in the insert soap being compressed.

It will also be noted that the bottom of cavity 86 and/or the apertures 89 are closed by slide 91 during such compression of the insert soap but it is to be understood that the provision of such a slide is optional because with insignia of small area and/or insert soap of sufficient hardness or dryness the extrusion through apertures 89 during compression will be negligible and will not disturb the re-arrangement of the grain for the insert or at most will only disturb the grain in the lower part of the insert.

The movement of plates 103 and 109 toward block 83 continues until adjustable stops 117 thereon abut against block 83 and adjustment of said stops 117 permits control of the distance which piston member 71 enters into the cavity 86. During said first step of the cycle, the thrust of springs 106 and 112 is exerted against springs 99 only through the soap material in cavity 86. The predominance of springs 99 prevents any appreciable movement of the cover member 69 and the difference between the resistance of springs 99 and the effort of springs 106 and 112 determines the pressure exerted on the insert soap in cavity 86, which pressure is sufficient to orient the grain in said insert soap.

Continued movement of frame member 72 after stops 117 on plate 103 abut against block 83 accomplishes the second step of my improved method and apparatus, as shown in Fig. 6. Such movement of frame member 72 after compression of the insert soap in cavity 86 and abutment of stops 117 with block 83 further increases the compression of springs 106 and 112 whose efforts are now exerted directly against the block 83 and springs 99 are now compressed. As a result cover member 69 is moved toward the mold member and the soap cake engaging surface 85 of projection 84 is moved against the display surface of the soap cake 29 within the frame 50 of the mold member and dowels 83' on block 83 are moved into corresponding recesses in said frame 50. At the same time, and as the third step of the cycle the plunger member 70 and the piston member 71 are both moved toward the soap cake but the lower faces of piston 104 and of plungers 110 are maintained in substantially flush relationship on account of the relative characteristics of the springs 106 and 112, see particularly Fig. 7. Since plate 109 has not moved relatively to plate 103, the slide 91, if provided, is still in closed position.

During the fourth step of the cycle, the distinctive inserts are projected or injected into the soap cake 29, see Fig. 8. The actuating means for said insert forming and injecting station moves the frame head 72 farther toward the mold member and spring 112 is compressed still more to exert a thrust on plate 109 and move the same toward block 83 of cover member 69. Such relative movement of plate 109 moves rises 116 of cam members 115 out of the slots 92 in slide 91 and springs 95 thus act to move one end of slide 91 against one of the dowels 83' on block 83 in which position the opening 97 in said slide 91 is opposite the ends of plungers 110 and in registry with the bottom of cavity 86, see Fig. 4.

Further movement of plate 109 toward block 83 projects plungers 110 through piston 104 and presses distinctive inserts 34' out of the compressed insert soap in cavity 86 and into the soap

cake 29. Since the apertures 89 in projection 84 are formed by molding around the cores or perforating plungers 61, such injection or insertion into the apertures 65 in soap cake 29 will be accompanied by a reforming or reshaping of said apertures 65 by the distinctive inserts 34' which themselves cut a portion or shaving 29' from the walls of apertures 65 in cake 29, as shown in Figs. 8 and 13. The movement of plate 109 and plungers 110 with respect to block 83 and projection 84 is limited by engagement of abutments 109' with the top of block 83. Said abutments 109' may be adjustable and are arranged so that the ends of plungers 110 are precisely flush with the cake engaging surface 85 of the cover member 69 at the completion of the fourth step of the cycle. If such soap cake engaging surface 85 is concave, as shown, the ends of plungers 110 are also concave to form therewith a smoothly curved surface.

The stroke of plungers 110 is preferably so selected or adjusted as to project into the soap cake 29 a distinctive soap insert 34' equal in length to one half the thickness of the soap cake 29. Since the apertures 65 extend more than half way into the cake 29, the soap material 29' which is scraped or shaved from the walls of apertures 65 by the inserts 34' will fill in the extra depth of said apertures 65, see Fig. 8. The stroke of the perforating plungers 61 may be increased or decreased depending upon the space required by the soap material removed by the reshaping of apertures 65 by the inserts 34'.

An important advantage of injecting the distinctive inserts 34' in the manner just described is that the outer ends of said inserts 34' may be formed to conform more or less to the display surface of the soap cake 29 without the necessity of a cut-off operation upon the inserts which leaves an objectionable shiny area on said display surface adjacent the inserts 34'. Another advantage of injecting the inserts 34' in the manner described is that the ends of plungers 110 may be formed with a curvature different and/or reverse from the curvature of the display surface of the cake 29, and abutments 109' may be adjusted so that the ends of plungers 110 at the end of their stroke extend slightly into the cake 29 to give a recessed effect. Alternatively, the ends of plungers 110 may be more sharply concave than the surface of cake 29, see Fig. 16, and abutments 109' may be adjusted so that only the edges of such concave ends of plungers 110 are flush with the display surface of cake 29 to give an embossed effect.

As previously suggested, the immediate injection of the inserts 34' after their formation and the reshaping of the apertures 65 by such recently formed inserts renders the contacting surfaces of the cake and inserts tackier and/or more adhesive so that the fixation of the inserts within the cake is improved. This advantage is obtained whether the apertures 65 are pre-formed in the cake 29 or whether the inserts 34' are of a harder and drier soap material and themselves effect the penetration of the soap cake.

Finally, the soap cake 29 with the insert 34' therein is subjected to a compression which finishes the surfaces of the cake. Such finishing operation is accomplished by further movement of the frame head 72 to bring the block 83 of cover member 69 against the face of hollow frame 50 of the mold member, see Fig. 9. During such finishing compression the ends of plungers 110 and the cake engaging surface 85 of the cover member are maintained in the same relative posi-

tions as at the end of the fourth step of the cycle or as maintained by the abutments 109'.

Upon the return stroke of the frame head 72 the compression on springs 99, 106 and 112 is relieved and the lower portion of frame head 72 abuts against adjusting nut 114 and nut members 108 respectively to return the plunger member 70 including plate 109 and plungers 110 and the piston member including plate 103 and piston 104 to their uppermost positions as shown in Fig. 1. At the same time springs 99 raise the cover member 69 including block 83, projection 84 and actuating rods 98 until nuts 98' thereon abut against the support member 67. Such return of frame head 72 to its upper position also places springs 101 under compression which act upon nuts 102 to assist in raising rods 98 and to urge nuts 98' against support member 67.

After such return of the parts of the insert

- 20 forming and injecting station to their uppermost or retracted positions, the strip 88 of insert soap is advanced manually or by any suitable mechanism to feed an additional supply of insert soap along the guideway 87 into the cavity 86 in block 83. As previously explained, the indexing means is timed to move the carrier and mold members thereon when the parts of all the stations are spaced from the carrier and the cycle may be repeated in the manner just described.
- 25 30 Inasmuch as the insert soap material is subjected to pressure in the cavity 86 to orient and/or rearrange the grain of such soap material so that such grain will be substantially parallel to the display surface after insertion into the soap cake,
- 35 35 the grain in the strip 88 of insert soap being fed into the compression chamber may extend in any direction. However, if the insert soap material is fed in strips or blocks having a depth equal to that of the insert 34' and if the soap grain in such strips or blocks is already in a predetermined plane, the construction and operation of the insert forming and injecting station may be simplified and improved in the manner next to be described.
- 40 45 50 In general such improvement of the insert forming and injecting station comprises the provision of a deeper guideway for feeding a soap strip equal in thickness to the depth of the inserts and the substitution of a cutter or cutters having the contour of the desired insignia in place of the piston 104 of the piston member 71 of the previously described insert forming and injecting station.

- 55 According to this other embodiment of the invention, the insert forming and injecting station comprises a cover member 69, one or more cutters 138, a plunger member 70, and an actuating means to operate said members. Said cover member 69 includes a block 83 carrying a projection 84 with a concave cake engaging surface 85 for engaging the display surface of a soap cake 29 within a mold member which is opposite the station and which comprises a hollow frame 50 and a movable bottom member 51. Said block 65 83 is provided with a guideway 139 for a strip 140 of insert soap material having its grain in a predetermined plane which is parallel to the bottom of said guideway 139 or substantially parallel to the display surface of cake 29 in the mold member. Said guideway 139 is preferably located with its lower surface even with the top of projection 84 and is of a depth and width sufficient to receive a strip 140 of distinctive or insert soap material having a depth or thickness equal to the desired depth of the distinctive inserts and hav-
- 70 75

11

ing a width greater than the lateral extent of the insignia. Said block 83 is also provided with one or more openings 141 extending from the top thereof to said guideway 139 and projection 84 is provided with apertures 89 corresponding to the shape of the insignia.

The actuating means for the cover member comprises a pair of actuating rods 98 attached to block 83 and extending upwardly through frame head 72 and support member 67. Coil springs 99 encircle rods 98 between nuts 100 thereon and support member 67. Nut members 98' on rods 98 abut the lower surface of support member 67. Coil springs 101 encircle rods 98 within frame head 72 and nuts 102 on rods 98 engage the upper ends of springs 101.

The cutter member comprises a plate 103 and one or more thin walled cutters 138 formed to the shape of the insignia and extending downwardly from plate 103. The actuating means for such cutter member comprises a pair of actuating rods 105 fastened to diagonally opposite corners of plate 103 and extending upwardly through said frame head 72. A pair of coil springs 106 encircle said rods 105 within the frame head 72, a pair of nuts 107 threaded to rods 105 adjust the compression on springs 106, and nut members 108 on rods 105 may abut the lower end of frame head 72.

The plunger member 70 comprises a plate 109 and one or more plungers 110 which have the same shape and contour as the desired insignia and which fit into the cutters 138 and into the apertures 89 in projection 84 of the cover member. Said plungers 110 extend downwardly from plate 109 which is provided near each corner with holes through which extend the pairs of actuating rods 98 and 105. An actuating rod 111 is attached at its lower end to the center of plate 109 and extends upwardly through the frame head 72. A coil spring 112 encircles said rod 111 between a nut 113 threaded thereon and the upper portion of frame head 72. An adjusting nut 114 is also threaded onto rod 111 and is adapted to abut against the lower end of frame head 72. A pair of abutments 109' are adjustably mounted or threaded into plate 109.

The frame head 72 of the preferred insert forming and injection station is operated as described previously and as shown in Fig. 15 and at the beginning of the cycle the actuating means spaces the plates 103 and 109 from the block 83 as shown in Fig. 1. In such position of plate 103 the lower ends of cutters 138 are above the guideway 139 so that the insert soap strip 140 can be fed therewith either manually or in some mechanical manner not shown. At the same time the bottom ends of plungers 110 are above guideway 139 and are preferably flush with the beveled ends 138' of cutters 138, see Fig. 16.

The first step of this preferred insert forming cycle of the machine is illustrated in Figs. 11 and 12 and takes place during the first part of the downward movement of frame head 72 of the actuating means. During such movement of frame head 72 the compression on springs 106 is increased to exert a thrust on actuating rods 105 and move plate 103 toward block 83 and the adjustable stops 117 into engagement therewith. Such movement of plate 103 moves cutters 138 through the strip 140 of insert soap to cut the distinctive soap inserts therefrom and the beveled lower edges 138' of said cutters 138 fit into or against the beveled upper edges 89' of the apertures 89 in projection 84. The spring 112 may

12

be arranged so that plate 109 and plungers 110 are not moved during said first step of the cycle or are at most only moved to bring the bottom ends of plungers 110 against the upper surface of strip 140. Also during said first step of the cycle the springs 99 oppose and prevent any appreciable movement of block 83.

Continued movement of frame member 72 after stops 117 on plate 103 abut against block 83 accomplishes the second step of the preferred method and apparatus as shown in Figs. 13 and 14. Further movement of frame member 72 places spring 112 under sufficient compression to move plate 109 toward plate 103 and relieves the compression on springs 106 so that block 83 and projection 84 are simultaneously moved toward the mold member, and cake engaging surface 85 on projection 84 abuts against the cake 29 in the mold members and dowels 83' move into corresponding recesses 50' in frame 50. As the downward movement of frame head 72 continues the plate 109 is moved downwardly and the distinctive soap inserts 34' are injected into the soap cake 29 and/or into apertures 65 previously provided therein. As before such injection of the inserts 34' reshapes or reforms the apertures 65. If the soap material for inserts 34' is sufficiently harder than the material of soap cake 29, the inserts 34' may be injected directly into the soap cake 29 without any previous provision of apertures therein.

Finally the abutments 109' on plate 109 engage the top of block 83 and the lower faces of plungers 110 are located in flush, recessed or protruding relationship with respect to the cake engaging surface 85 on projection 84. Again the whole insert forming and injecting station may be pressed to exert a final finishing operation upon the composite soap cake 29 and distinctive insert 34'.

During the return of the frame head 72 to its uppermost position, the plates 103 and 109 are displaced from block 83 and returned to their original positions. The retraction of cutter or cutters 138 from the strip 140 of insert soap will tend to carry the said strip 140 along but the upper wall of the guideway 139 acts as a stripper to prevent this. Thus it will be understood that the opening or openings 141 in block 83 need not correspond at all to the contour of the cutter or cutters 138 as long as the insert soap in strip 140 is cleanly stripped from the cutters 138.

After the insert injection has been accomplished and the carrier rotated, the rise 49 of cam member 47 will radially move the stem 55 and bottom members 51 of the mold member to eject the finished composite soap cake therefrom.

While various forms of the invention have been shown herein, it is to be understood that invention may be accomplished in still other forms or arrangements, for instance it is clear that the actuating means or mechanism for the various stations can be provided in a variety of ways. Consequently, the present disclosure is to be construed only in an illustrative sense and the scope of the invention is defined in the claims which follow.

I claim:

1. In an apparatus for providing insignia in a soap cake, the combination with a mold assembly provided with a cavity for a soap cake and having a well provided with an aperture having the shape and size of the desired insignia, of a plunger member movable through a body of

distinctive soap material, cooperating with and entering the apertured wall simultaneously to form a soap insert of a definite depth and to move the same through said apertured wall and into said soap cake, and an actuating means operatively connected to said plunger member and for moving the same into and through said aperture for soap insert formation and movement.

2. In an apparatus for providing distinctive insignia in a soap cake, the combination with a mold member provided with a cavity for containing a soap cake, and a cover member for said mold member and provided with an aperture having the shape and size of the desired insignia, of an insert forming and injecting means including a plunger member cooperating with said apertured cover member simultaneously to form and move within said aperture a soap insert, and actuating means operatively connected to said cover member and to said plunger member and for respectively moving said cover member to enclose said cavity and to engage a soap cake therein, and moving said plunger member to form within said aperture an insert of distinctive soap material and to move the same through the aperture in said cover member and into said soap cake.

3. In an apparatus for providing distinctive insignia in a soap cake, the combination with a mold member provided with a cavity for containing a soap cake, and a cover member for enclosing the cavity in said mold member, having a surface for engaging a soap cake in said cavity, and provided with an aperture having the shape of said insignia, of a forming means including a plunger member having the shape of said insignia, and actuating means connected to and for moving said plunger member toward said cavity and through the aperture in said cover member until the end of said plunger member is substantially flush with the cake engaging surface of said cover member, and for then pressing said cover member and plunger member simultaneously toward the soap cake.

4. In an apparatus for providing distinctive insignia in a soap cake, the combination with a mold assembly provided with a cavity for containing a soap cake and having a wall provided with an aperture having the shape and size of said insignia and provided with a cavity for soap material distinctive from said soap cake, of a forming means for forming an insert of distinctive soap material including a plunger cooperating with the apertured wall simultaneously to form and move within said aperture a distinctive soap insert, and an actuating means connected to and for moving said plunger through the second mentioned cavity and through the aperture in said wall to form therein an insert of distinctive soap material and to move said insert into said soap cake.

5. In an apparatus for providing distinctive insignia in a soap cake, the combination with a mold assembly provided with a cavity for containing a soap cake and having a wall provided with a cavity for distinctive soap material and provided with an aperture shaped like said insignia and extending from one cavity to the other, of a forming means including a piston member having the shape of the second mentioned cavity and including a plunger member having the shape of said insignia, and actuating means connected to and for moving said piston and plunger members simultaneously to compress

a distinctive soap material in said second mentioned cavity and then moving said plunger member with respect to said piston member to force a distinctive soap insert through said aperture and into said soap cake.

6. In an apparatus for providing distinctive insignia in a soap cake, the combination with a mold assembly provided with a cavity for containing a soap cake and having a wall with a soap engaging surface, provided with a cavity for distinctive soap material, and provided with an aperture shaped like said insignia and extending from the second mentioned cavity to said cake engaging surface, of an insert forming an injecting means including a piston member fitting into the second mentioned cavity and provided with an aperture having the shape of said insignia, and including a plunger member having the shape of said insignia and extending into the aperture in said piston member, and actuating means for operatively connecting to said piston and plunger members for moving them simultaneously to compress the distinctive soap material and for then moving said plunger member with respect to said piston member to move a distinctive insert through the aperture in said cover member until the end of said plunger is substantially flush with said cake engaging surface.

7. In an apparatus for providing distinctive insignia in a soap cake, the combination with a mold assembly provided with a cavity for containing a soap cake and having a wall with a soap cake engaging surface, provided with a cavity for distinctive soap material, and provided with an aperture shaped like said insignia and extending from the second mentioned cavity to said cake engaging surface, of an insert forming and injecting means including a piston member fitting into the second mentioned cavity and provided with an aperture having the shape of said insignia, and including a plunger member having the shape of said insignia and extending into the aperture in said piston member, a slide member in said apertured wall for covering the apertures therein and provided with an opening adapted to uncover said aperture, actuating means operatively connected to said piston and plunger members for moving them simultaneously to compress the distinctive soap material and for then moving said plunger member with respect to said piston member and toward the mold member, and an operative connection between said plunger member and said slide member and for moving said slide member to uncover the aperture extending from said second mentioned cavity when said plunger member is moved with respect to said piston member.

8. In an apparatus for providing distinctive insignia in a soap cake, the combination with a mold assembly provided with a cavity for containing a soap cake and having a wall with a soap engaging face, provided with a guideway for a strip of distinctive soap material, and provided with an aperture having the shape of said insignia and extending from said guideway to said engaging surface, of an insert forming and injecting means including a hollow cutter member provided with an opening in the shape of said insignia, and including a plunger member fitting into the opening in said hollow cutter member, and actuating means operatively connected to said cutter and plunger members for first moving said hollow cutter member through said guideway to cut an insert from a strip of distinctive

15

soap therein and for then moving said plunger member to eject the insert from said cutter member, move the same through said aperture and into a soap cake within said cavity.

9. In an apparatus for providing distinctive insignia in a soap cake, the combination with a mold assembly provided with a cavity for containing a soap cake and having a wall with a soap engaging face, provided with a guideway for a strip of distinctive soap material, and provided with an aperture having the shape of said insignia and extending from said guideway to said cake engaging surface, of an insert forming and injecting means including a hollow cutter member provided with an opening in the shape of said insignia and movable into continuous alignment with the aperture in said wall, and including a plunger member movable through the opening in said hollow cutter member, and actuating means operatively connected to said cutter and plunger members for first moving said hollow cutter member through said guideway to cut an insert from a strip of distinctive soap therein and into continuous alignment with the aperture in said wall and for then moving said plunger member through said hollow cutter member to eject the insert therefrom and to inject said insert into a soap cake within said mold cavity.

10. In an apparatus for providing distinctive insignia in a soap cake, the combination with a mold assembly provided with a cavity for con-

16

taining a soap cake and having a wall with a soap engaging face, provided with a guideway for a strip of distinctive soap material, and provided with an aperture having the shape of said insignia and extending from said guideway to said cake engaging surface, of an insert cutting and injecting means including a hollow cutter member provided with an opening having the shape of said insignia, and including a plunger member having the shape of said insignia, co-operative surfaces on the lower end of said cutter member and around the guideway end of the aperture in said cover member, and actuating means operatively connected to said cutter and plunger members for first moving said hollow cutter member through said guideway to cut an insert from a soap strip therein and to bring said co-operative surfaces into engagement, and for moving said plunger member through said hollow cutter member and the aperture in said cover member to inject a distinctive insert into a soap cake within the mold cavity.
